UNITED STATES PATENT OFFICE

WILLIAM S. PRITCHARD, OF DETROIT, MICHIGAN, ASSIGNOR TO MOTOR PRODUCTS CORPORATION, OF DETROIT, MICHIGAN, A CORPORATION OF NEW YORK

PULLMAN WINDOW

Application filed February 27, 1928. Serial No. 257,485.

The invention relates to window construction and more particularly to an improved means for detachably securing the glass panel within the sash.

5 The invention has as one of its primary objects to provide a window of the above type distinguished by its simplicity of construction and facility with which the same may be attached to the standard car construction 10 and with which the usual glass panel may be installed, all of which not only enhances its value both mechanically and commercially, but provides a design of a strong and durable nature.

15 The invention finds particular utility in Pullman car construction wherein it is necessary to frequently replace the glass panel due to breakage or other defects. In the particular type of window now more or less 20 universally employed, serious disadvantages have been commonly experienced in assembling the glass panel in the sash owing to the various complicated means utilized for this purpose. The present invention as 25 briefly outlined above offers the possibility of eliminating complicated and inefficient securing means for the glass and renders possible the production of a commercially satisfactory window construction in which 30 the glass panel may be readily installed.

It is a further object of the present invention to provide a construction wherein the glass panel securing means not only functions to detachably hold the glass panel in 35 position within the sash, but also cooperates with a portion of the Pullman car to accurately guide the window during the opening or closing of the same.

40 While in particularizing upon the advantages and features of the present invention, particular stress has been placed upon the association of the window with Pullman car construction. It will be immediately apparent to those skilled in this art that the 45 invention may be used in whole or in part in connection with various other forms of constructions where windows are desired.

50 Many of the advantages and much of the commercial value and acceptability of the invention is attributed to the construction

of the sash, these advantages being obtained particularly because of the simplicity, of the construction and the minimum number of parts employed for securing the glass panel in place. The invention therefore depends 55 for some of its advantages upon the specific details of construction illustrated and about to be described.

Other objects and novel features of construction will be made more apparent as this 60 description proceeds especially when considered in connection with the accompanying drawings wherein

Figure 1 is a side elevation of a window constructed in accordance with my invention, 65

Figure 2 is a sectional view taken on the plane indicated by the line 2—2 of Figure 1,

Figure 3 is a sectional view on the line 3—3 of Figure 1.

Figure 4 is a sectional view on the line 4—4 70 of Figure 1.

Referring now to the drawings, it will be noted that there is illustrated generally a portion of a standard Pullman car construction in which 10 is a pillar having secured upon 75 the outer surface thereof, a substantially U-shaped reinforcing member 11 terminating in the lateral flanges 12 and 13. Spaced inwardly from the front face of the pillar and secured to the side surface 14 thereof 80 is a guide member 15, which as shown cooperates with the lateral flange 12 to form a run-way 16 for the vertically movable glass panel 17 constituting the outer window of the Pullman car. The inner window 18 being 85 slidably mounted in the runway 19 formed by the inner surface of the guide 15 and the usual latch rack 20.

Referring now to the particular construction of the sash members 21 and 22 for the 90 inner and outer windows 17 and 18 respectively, it will be noted that these members are preferably constructed of sheet metal and are provided with stiles 23 and upper and lower rails 24 and 25 respectively, which as 95 shown are substantially channel-shaped in cross section and are secured together in any suitable manner such for example by means of the corner brackets 26. The outer walls 27 and the inner walls 28 of the rails and 100

stiles of the outer and inner sash members 21 and 22 respectively are bent inwardly intermediate the ends thereof as indicated at 28' forming shoulders 29, which as shown terminate in open return bent portions 30, while the inner walls 31 and the outer walls 31' of the stiles and rails of the outer and inner sash members 21 and 22 respectively are formed with an L-shaped rabbet 32 for receiving the usual packing for the glass panel and terminate in open return bent portions 33. The outer ends 34 of the portions 33 project into the open return bent portions 30 and the outer ends 35 of the return bent portions 30 project into the open return bent portions 33 so that an interlocking engagement is accomplished between the opposite walls of the rails and stiles. Thus from the foregoing, it will be immediately apparent that the rails and stiles are formed of a single piece of metal bent to form a closed channel and have the opposite ends thereof held in interlocking engagement. The bottom 36 of the lower rail of the sash 21 is bent upwardly as indicated at 37 forming a longitudinally extending pocket 38 for receiving a suitable weather excluding strip 39 having the projections 40 arranged to engage the stool 41. This lower rail is also provided with the usual sliding ventilator construction indicated generally at 42. To prevent rattling of the windows, I provide the anti-rattler members 43, which as shown are of the usual construction and are secured to the stiles adjacent the outer edges thereof, and are arranged to yieldably engage the outer and inner walls of the guide member 15.

In order to provide a neat construction and at the same time effectively secure the glass panel within the sash, I provide the glazing strips 44 and 45 secured respectively to the outer walls of the rails and stiles of the sash 21. The rails and stiles of the inner sash 22 are also provided with glazing strips 46 and 47 respectively, which as shown are secured to the inner walls of the stiles and rails. The strips 44 and 46 are provided at one end with the packing engaging portions 48 and at the opposite ends with the lateral projections 49 arranged to seat upon the shoulder 29 and engage the return bent portions 33. The strips 45 and 47 which are secured to the stiles of both the inner and outer sash members 21 and 22 differ from the strips 44 and 46 in that they are provided with return bent portions 50 and 51 intermediate the ends thereof. These return bent portions engage the shoulders 29 of the stiles and abut the return bent portions 33 thereof and terminate in lateral flanges 52 and 53 respectively, which as shown are positioned adjacent and spaced laterally from the walls 27 and 27' of the stiles. The flange 52 extends across the outer surface of the flange 12 and is provided with a longitudinally extending bead

53' having a bearing engagement with the outer surface of the flange 12 to accurately guide the window during opening or closing of the same. With such an arrangement, the amount of frictional resistance between the relatively removable parts is reduced to a minimum owing to the fact that the inner arcuate surface of the bead is the only part of the flange 52 that actually engages the flange 12. It will further be noted that the flange 52 is of substantially the same length as the window and is reinforced at the lower end thereof by means of the clip 54 secured to the bottom rail of the sash 21 and having a portion 55 embracing the flange 52. The flange 53 of the inner glazing strip also serves as a guide for the inner window and is provided with a longitudinally extending bead 56 arranged to engage the outer surface 57 of the latch rack 20. The flange 53 in addition to cooperating with the latch rack to accurately guide the window also functions to fill the space between the stiles of the sash 22 and the latch rack.

For securing the glazing strips to the stiles and rails, I provide headed elements 57 extending through threaded apertures 58 formed in the glazing strips and anchored in the return bent portions 30 and 33 of the stiles and rails. As shown the headed elements are provided with an enlarged threaded portion 59 and a reduced shank portion 60, the latter having a length substantially greater than the length of the threaded portion. With this arrangement, when it is desired to remove the glazing strips, it is not necessary to remove the headed elements from the strips but merely to unscrew the same from the stiles and rails. Thus the danger of the elements working loose and becoming lost is eliminated and the attaching and detaching of the glazing strips is greatly facilitated. If, however, it is desired to remove the elements from the strips, the former are merely backed out through the threaded apertures 58. It will also be noted that the elements 57 upon threaded engaging the return bent portions 30 and 33 engage four thicknesses of metal, thereby providing ample threads for these elements so that the latter may be securely tightened to rigidly secure strips upon the stiles and rails.

As described the window is of simple construction and of a minimum number of parts, it being noted that the glazing strips 46 and 47 in addition to securing the glass panel in position cooperate with portions of the car to accurately guide the windows during the sliding movement of the same.

What I claim as my invention is:

1. In a window construction, the combination with a support, of a pair of spaced sash members slidably mounted upon said support, glass panels for said sash, glazing strips secured to said members having one end en-

- gageable with said panels to hold the same in position and having a return bent portion intermediate the ends thereof engageable with the sash and terminating in lateral flanges having portions arranged to engage the support for guiding the sash members during the sliding movements thereof. 5
2. In a window construction, a sash including a member formed from a single sheet of metal bent into channel form and having interlocking return bent portions at the free edges thereof, a glass panel for said sash, and a glazing strip secured to the interlocking return bent portions and having a portion cooperating with the member aforesaid to form a packing receiving channel. 10
3. In a window construction, the combination with a support, of a sash slidably mounted upon said support, a glass panel for said sash and a glazing strip for said panel secured to said sash having a lateral flange formed with a longitudinally extending bead engageable with said support to accurately guide the sash during the sliding movements thereof. 20
4. In a window construction, the combination with a support, of a sash slidably mounted upon said support, a glass panel for said sash, a glazing strip for said panel having a laterally projecting flange extending substantially the full length of the sash and having a portion engageable with the support for guiding the sash, and means upon said sash, and engageable with the lateral flange aforesaid for holding the portion aforesaid into engagement with said support. 30
5. In a window construction, the combination with a support, of a sash slidably mounted upon said support, a glass panel for said sash, a glazing strip for said glass panel having a laterally projecting flange extending substantially the full length of the sash and having a portion engageable with the support for guiding the sash, and a member secured to said sash adjacent the lower end thereof having a portion embracing said flange for holding the portion aforesaid thereof in engagement with the support. 40
6. In a window construction, a sash, a glass panel for said sash, a glazing strip for said glass panel detachably secured to said sash, and means for securing said strip to said sash including a headed element having a threaded portion threadedly engaging said sash and having a shank portion of reduced diameter and of a length substantially greater than the length of said threaded portion whereby the glazing strip may be detached from the sash without removing the said headed element therefrom. 50
7. In a window construction, a sash, a glass panel for said sash, a glazing strip for said glass panel detachably secured to said sash and means for securing said strip to said sash including a headed element having a 60
- threaded portion and a shank portion so proportioned that the strip may be detached from the sash without removing the headed element therefrom. 70
8. In a window construction, a sash, a glass panel for said sash, a glazing strip for said glass panel detachably secured to said sash including a headed element having a portion threadedly engaging said strip and sash and having a reduced shank portion slidably engaging the threaded opening in said strip and being so proportioned with respect to said threaded portion that the latter may be detached from the sash without removing the threaded element therefrom. 75
9. In a window construction, a sash, a glass panel for said sash, a glazing strip for said glass panel having a portion spaced from said sash, and means for detachably securing said glazing strip to said sash including a headed element having a shank portion extending freely through said strip and terminating in an enlarged threaded portion anchored in said sash, said shank and threaded portions being so proportioned with respect to the space between the strip and sash that the former may be detached from the latter without removing the headed element from the strip. 80
10. In a window construction, the combination with a support, of a sash having a portion slidably engaging one side of the support and having another portion forming a seat for a glass panel, a glazing strip having the inner edge thereof engageable with the glass panel for maintaining the latter in engagement with the seat aforesaid and having a portion of the outer edge thereof slidably engageable with the opposite side of the support to guide the sash throughout its movement, said strip further having a laterally projecting portion intermediate the edge portions aforesaid and engageable with the sash to position the outer edge portion of the strip in proper spaced relation to the adjacent face of the sash, and the means for securing the strip in position upon the sash. 90
